UNITED STATES PATENT OFFICE.

FRANK F. BURTON, OF MOUNT CARMEL, CONNECTICUT, ASSIGNOR TO WINCHESTER REPEATING ARMS CO., OF NEW HAVEN, CONNECTICUT, A CORPORATION.

LEAF-SIGHT FOR FIREARMS.

1,338,121.

Specification of Letters Patent. Patented Apr. 27, 1920.

Application filed November 1, 1919. Serial No. 335,017.

To all whom it may concern:

Be it known that I, FRANK F. BURTON, a citizen of the United States, residing at Mount Carmel, in the county of New Haven 5 and State of Connecticut, have invented a new and useful Improvement in Leaf-Sights for Firearms; and I do hereby declare the following, when taken in connection with the accompanying drawings and 10 the characters of reference marked thereon, to be a full, clear, and exact description of the same, and which said drawings constitute part of this application, and represent, in—

15 Fig. 1, a view in rear elevation of a leaf-sight embodying my invention and showing the leaf in its elevated position.

Fig. 2, a view thereof in side elevation.

Fig. 3, a detached view in rear elevation 20 of the slide-body.

Fig. 4, a plan view thereof.

Fig. 5, an end view thereof.

Fig. 6, a detached view of the slide assembly-screw.

25 Fig. 7, a detached view in rear elevation of one of the interchangeable sight-plates.

Fig. 8, a reverse plan view thereof.

Fig. 9, a detached view in rear elevation of another interchangeable sight-plate.

30 Fig. 10, a corresponding view of another interchangeable sight-plate.

Fig. 11, a corresponding view of another interchangeable sight-plate.

Fig. 12, a reverse plan view thereof.

35 Fig. 13, a reverse plan view of still another form which the interchangeable sight-plate may assume.

My invention relates to an improved leaf-sight for firearms, the object being to provide a simple and convenient sight of the 40 type described, with interchangeable sight-plates to permit a given leaf-sight fixture to be adapted by the interchange of a series of specialized sight-plates to meet the idiosyncrasy or personal equation of the user of the arm.

With these ends in view my invention consists in a leaf-sight provided with a series of interchangeable sight-plates formed 50 at their respective ends with positioning-flanges and held in place by a single centrally arranged slide assembly-screw. My invention further consists in certain details of construction as will be hereinafter described and pointed out in the claims.

In carrying out my invention as herein shown, I employ a leaf-sight comprising a sight-base 2, a leaf 3 turning on a pivot 4, and a leaf-spring 5, all of standard construction. Upon the leaf 3, I mount a slide-body 6 having a central block 7 which enters the longitudinal opening 8 in the leaf 3. The left hand side of this block is formed with segmental screw threads 9 which are engaged by an elevation screw 10 furnished 60 at its upper end with a knurled finger-button 11 located in a slot 12 in the outer end of the leaf 3.

The slide-body 6 is formed at its ends with rearwardly extending arms 13 formed 70 with oppositely located positioning-slots or notches 14 respectively receiving positioning-flanges 15, located at the ends of a series of interchangeable sight-plates 16 which will vary in number and in sighting details 75 according to requirements. Each of these plates is formed with a central screw-hole 17 receiving the slide assembly-screw 18 which enters a horizontal screw-hole 19 in the block 7 of the slide-body 6, the said screw-hole 19 being located centrally between the said notches 14.

To interchange the sight-plates, it is only necessary to remove the screw 18 and replace the plate by another, using the same 85 screw for securing it in place.

The differentiation of the sight-plate 16 will depend upon the idiosyncrasy of the user and the character of the use. Thus, the sight-plate 16 of Fig. 1, is formed with 90 a small sight-opening 20 while the sight-plate 16 of Fig. 7 is formed with a larger sight-opening 21. The sight-plate 16 of Fig. 7 is also furnished with an upturned battle-sight 22 which, it is to be understood, 95 is used only in the depressed position of the sight-leaf 3. Fig. 9 is a detached view of the sight-plate 16 of Fig. 1. The sight-plate 16 of Fig. 10 has a larger sight-opening 23 than is shown in any of the other 100 sight-plates. The sight-plate 16 of Figs. 11 and 12 is peculiar in having its battle-sight 24 upturned from its upper end while the sight-plate 16 of Fig. 13 is peculiar in having a notched battle-sight 25. Of course, 105 the sight-plates shown and described are only illustrative of some of the interchangeable sight-plates that may be employed. In respect of their sighting features, they will be differentiated, but in respect of their as- 110

sembly features they will be alike in being provided at their respective ends with positioning-flanges and with a central screw-hole for the reception of the slide assembly

5 screw.

I claim:

1. A leaf-sight for firearms, comprising a sight-base, a pivotal leaf, a vertically adjustable slide-body mounted thereupon and 10 formed at its respective ends with positioning-notches, a series of differentiated sight-plates, each formed at its respective ends with positioning-flanges adapted to enter the said notches of the slide-body, and 15 means for securing the sight-plates to the slide-body.
2. A leaf-sight for firearms, comprising a sight-base, a pivotal leaf, a vertically adjustable slide-body mounted thereupon and 20 formed at its respective ends with positioning-members, a series of interchangeable differentiated sight-plates, each formed at its respective ends with positioning-members adapted to co-act with the correspond-

ing members of the slide-body, one or more 25 of the said sight-plates being provided with up-turned battle-sights; and means for securing the said sight-plates to the slide-body.

3. A leaf-sight for firearms, comprising a 30 sight-base, a pivotal leaf, a vertically adjustable slide-body mounted thereupon and formed at its respective ends with positioning-members and with a centrally located screw-hole, a series of interchangeable 35 differentiated sight-plates, each formed at its respective ends with positioning-members and with a screw-hole located centrally between its ends, and a screw passing through the said screw-holes for securing the plates 40 to the body.

In testimony whereof I have signed this specification in the presence of two subscribing witnesses.

FRANK F. BURTON.
